UNITED STATES PATENT OFFICE.

CHARLES W. SHANABERGER, OF ARROW, PENNSYLVANIA.

TROLLEY CONTROLLER.

Application filed June 1, 1920. Serial No. 385,683.

To all whom it may concern:

Be it known that I, CHARLES W. SHANABERGER, a citizen of the United States, and a resident of Arrow, in the county of Somerset and State of Pennsylvania, have invented a new and useful Improvement in Trolley Controllers, of which the following is a specification.

My invention relates to electric locomotives for mining and other industrial purposes and consists in mechanism for lowering and shifting the locomotive trolley. Hitherto when it has been desired to shift the trolley or to replace it if accidentally dislodged from the power wire, the operator was compelled to leave the car or crawl over the top of same. Both of these actions are inconvenient and, at times, fraught with no small amount of danger. In some restricted passages, they are impossible. Often the locomotive is operated with the trolley running backwards because it is inconvenient or impractical to shift it. It is well known that the difficulty outlined here is responsible annually for large numbers of serious accidents.

The object of my invention is to avoid these difficulties by enabling the operator to control the trolley from his position on the locomotive.

In the accompanying drawings which illustrate a preferred embodiment of my invention, Figure 1 is a side elevation of a mine locomotive equipped with my device; Fig. 2 is a similar elevation, on a larger scale, of the trolley mounting and its operating mechanism; Fig. 3 is a vertical section thru an elevation of the elements shown in Fig. 2, and Figs. 4 and 5 are a section and elevation, respectively, of details referred to hereinafter.

Secured to the locomotive frame is a cylindrical bracket 1. Telescoped therein is a rotatable cylinder 2 which pivotally supports the locomotive trolley 3. The latter is yieldingly maintained in its erect position by a vertical rod 4 slidably and rotatably mounted in cylinder 2.

Complete and convenient control of the trolley by the operator is secured by providing means, operable from his seat, for lowering rod 4 and rotating cylinder 2.

Two integral ears 5 extend upwardly from the top of cylinder 2 and mount a horizontal pivot member 6 for the trolley arm. Rod 4

screwed thereon forms an upper, sliding bearing for the rod in cylinder 2 and also forms a seat for a coil spring 9 which is compressed between nut 8 and the lower end 60 of cylinder 2 and consequently tends to raise rod 4 but is limited in this tendency by the weight of the trolley arm on rod 4 and the engagement of the arm with the trolley wire 10.

A segmental socket member 11 is pivotally mounted on rod 4 at 12 and it journals a plurality of rollers 13 which are arcuately disposed and form an anti-friction seat for the round portion 14 of the trolley arm. 70 The lower end of rod 4 extends thru central openings in cylinder 2, bracket 1 and a rack element 15, which is slidably mounted between downwardly projecting flanges 16 on bracket 1. Rack 15 is rectangular in section which prevents its rotation between flanges 16. A collar 17 is pinned to the lower end of rod 4 and an anti-friction thrust bearing 18 is positioned between the collar 16 and rack 15. A pinion 19 is journaled in flanges 16 and is provided with an integral radial lever arm 20 whereby the pinion may be rotated and the rack moved accordingly.

Obviously the movement of arm 20 in an 85 anti-clockwise direction will move rack 15 and rod 4 downwardly, compressing spring 9 and permitting the weight of trolley arm 3 to lower the trolley wheel from the power wire. Arm 20 may be actuated by the locomotive operator at a point remote from the arm by means of a cable 21, secured at one end to arm 20, passing over a sheave 22 and secured at the other end to a lever 23 fulcrumed on the locomotive frame convenient 90 to the operator's hand. As shown, the lever 23 is located at a point adjacent to the operator's station and is provided with a segmental ratchet and handle actuated ratchet-engaging pin for locking the lever in position to retain the trolley in a lowered position.

When arm 20 is released, spring 9 will raise rod 4 and trolley arm 3 as far as wire 10 or as rack 15 (which is an elongated washer between the bottom of bracket 1 and bearing 18) will permit.

The upper portion of cylinder 2 is equipped with a horizontal sprocket 24 and a chain 25 connects same with a sprocket 26 mounted on the locomotive frame adjacent 110 lever 23 and at a point convenient to the

27 by which it may be turned and the trolley rotated on its mounting. Lever 23 and sprocket 26 and the parts controlled by them cooperate to give the operator complete control of the trolley arm without leaving his position.

In the drawings, I have shown a motion retarding device located between the trolley arm and its rotatable support 24. As shown, 10 an open ended cylinder 28 is mounted on the arm 3 and is provided with a piston 29 which projects into the open end thereof, is reciprocable relatively thereto, and is guided by means of a guide mounted on the trolley arm. 15 As shown, the piston 29 is operatively connected to the brackets 5 by means of a pair of links 30. The forward end of the cylinder is provided with an air port 31 for establishing communication between the exterior and interior of the cylinder. This port is controlled by a ball check 32 suitably caged and so located as to respond to increased pressure within the cylinder and close the port 31. A restricted aperture 33 20 is provided in the cylinder wall and is in open communication with the exterior of the cylinder and the atmosphere. With this arrangement, the trolley arm may be readily shifted, but an upward swing will be retarded by the confined air within the piston which cannot escape except through the restricted port 33. A downward swing of the arm will retract the piston, with relation to the cylinder, and the valve 32 will open in 25 response to the reduction in pressure within the cylinder and will permit a free flow of air into the cylinder.

It may be desirable to mount the operating lever and sprocket at either right or left of 40 the bracket 1 and I provide the bracket with sheave and pinion mountings on both sides so that it is unnecessary to manufacture the bracket in right hand and left hand models and also making it possible to reverse the 45 position of the operating lever and sprocket at any time after its assembly with the locomotive, if occasion therefor arises. This is accomplished by shifting sheave 22 and pinion 19 to the opposite side of the bracket and 50 by removing nut 17 to permit reversal of rack 15. This detail is optional and but one of the likely modifications which I contemplate in the commercial development of my invention without involving any departure 55 from its principles.

I claim:

1. In a trolley controller, a bracket, a member journaled therein to rotate about a vertical axis and provided with a bearing 60 adapted to pivot one end of a trolley arm, a rod positioned axially of said member and

provided with a trolley arm engaging element at its upper end, a spring adapted to push said rod upwardly, a vertical rack secured on said rod, a pinion mounted on said bracket and meshing with said rack, means for rotating said member about its axis and independent means for rotating said pinion, both of said means being operative from a point remote from said bracket. 70

2. In a trolley arm mounting, a horizontal pivot for the trolley arm and adjacent the end thereof, an arcuate edge on said arm adjacent said pivot and facing downwardly, an arcuate bearing for said edge having a 75 horizontal pivot on a bearing support member, and yielding means for upholding said support member and upholding said trolley arm through said arcuate pivoted bearing.

3. A trolley arm mounting, comprising a 80 fixed support, a trolley arm support rotatively mounted thereon, a trolley arm pivotally mounted on said rotatable support, a reciprocable arm-actuating member mounted on said rotatable support, means for reciprocating said member, means for rotating said rotatable support, and separate means located remote from said arm for controlling both of said last mentioned means. 85

4. A trolley arm mounting comprising a 90 fixed support, a trolley arm support rotatively mounted thereon and having a cylindrical extension projecting into an aperture of the fixed support, a trolley arm pivotally mounted on said rotatable support, a reciprocable arm-actuating member extending 95 through the cylindrical extension of said arm support and operatively engaging said arm, a coiled spring surrounding said member and surrounded by said extension and 100 operating between said member and said arm support to normally hold said arm upwardly, means for reciprocating said member and means for rotating said arm support.

5. A trolley arm mounting comprising a 105 fixed support, an arm support rotatively mounted thereon, a trolley arm pivoted on said arm support to swing in a vertical plane and having a curved bearing surface formed thereon adjacent the pivoted end thereof, 110 an arm-actuating member reciprocatively mounted on said rotatable support, an arcuate bearing pivotally mounted on said member and engaging the curved bearing surface of said arm, and a spring acting between said arm support and said member for holding said bearing in supporting engagement with said arm. 115

In testimony whereof, I have hereunto subscribed my name this 24th day of May, 120 1920.

CHARLES W. SHANABERGER.
